UNITED STATES PATENT OFFICE.

GEORGE WASHINGTON SIMONS, OF THURSTON, NEW YORK.

GATE.

SPECIFICATION forming part of Letters Patent No. 706,263, dated August 5, 1902.

Application filed April 24, 1902. Serial No. 104,448. (No model.)

To all whom it may concern:

Be it known that I, GEORGE WASHINGTON SIMONS, a citizen of the United States, residing at Thurston, in the county of Steuben and 5 State of New York, have invented certain new and useful Improvements in Gates; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to new and useful 15 improvements in gates, and especially to a folding panel-gate which is so constructed that it may be held in a partially-folded relation or allowed to rest its weight upon the ground, relieving the hinges when the gate is 20 closed.

Another feature of the present invention consists in the provision of a pivoted brace which is held at its free end by a guide-plate against the side of the gate, whereby the gate 25 whether partially folded or open may be securely held rigid.

Other features of my invention reside in the novel details, combinations, and arrangement of parts, as will be hereinafter more 30 fully described and then specifically defined in the appended claim.

The invention is clearly illustrated in the accompanying drawings, which, with the letters of reference marked thereon, form a part 35 of this application, and in which drawings similar letters of reference indicate like parts throughout the views, in which—

Figure 1 is a side elevation of my improved gate closed. Fig. 2 is a view showing the 40 gate partially folded and held in a partially-folded position. Fig. 3 is a horizontal sectional view through the brace and guard-plate.

Reference now being had to the details of 45 the drawings by letter, A designates a post having a hinge-bar B journaled to the post by means of staples C. This bar is preferably mounted on the post along its central or middle portion and has its ends outwardly

and upwardly bent, as illustrated, and on these 50 ends the gate is hung. The gate comprises the end bars D D and intermediate bars D' D', between which the longitudinal strips E of the gate are pivotally connected. The rear bars have hinge-sockets F, which are mounted 55 upon the ends of the hinge-bar B. To the upper and lower longitudinal strips of the gate are pivotally connected the ends of the inclined braces H H, the forward ends of said braces being held together and in a fixed 60 relation to each other by means of the plate K. The forward end of said plate K is adapted to rest parallel to the rear face of one of the bars D' whether the gate be open or partially folded. A plate M is provided, which 65 is fastened to the outer face of a bar D, with one of its longitudinal edges projecting toward the hinged end of the gate and beyond the edge of the bar to which it is fastened.

Pivoted to the upper portion of the gate, 70 preferably to the upper longitudinal strip, is a bar R, the free end of which is adapted to swing down in the path of the pivoted V-shaped brace to hold the gate partially folded. As the gate is partially folded, which is effected by raising the forward end of same, the free end of the V-shaped brace will swing down, and as the gate is returned to its horizontal position the free end of the brace will lie adjacent to the central or middle portion 75 of the end bars of the gate, as illustrated. When it is desired to relieve the hinges of the weight of the gate, the forward end of the latter may be depressed, so that the forward bars will rest upon the ground. 80

From the foregoing it will be observed that by turning the hinge bar or rod laterally the gate will be allowed to swing in one direction or the other, so that the gate will be when wide open in line with the front face of the 90 gate-post. The gate may be partially folded and held in such position by means of the pivoted bar, thus being adjusted to clear obstructions, snow in winter-time, &c. 85

Having thus described my invention, what 95 I claim to be new, and desire to secure by Letters Patent, is—

A folding panel-gate comprising the longi-

tudinal strips with end and intermediate pivotal, cross-bars, the plate M fastened to the cross-bar at the free end of the gate, the bars H pivoted to the top and bottom strips of the 5 gate, and fastened together at their forward ends, suitably braced, and guided behind said plate M and one of the said cross-bars, and a pivoted brace R adapted to contact

with one of said bars H, as shown and for the purpose set forth.

In testimony whereof I affix my signature in presence of two witnesses.

GEORGE WASHINGTON SIMONS.
